DESIGN FOR AN ASH TRAY

Orvin H. Chandler, William W. Chandler, and
Claremont R. Copeland, Cocoa, Fla.

Application February 26, 1941, Serial No. 99,228

Term of patent 3½ years

To all whom it may concern:

Be it known that we, Orvin H. Chandler, William W. Chandler, and Claremont R. Copeland, citizens of the United States of America, residing at Cocoa, county of Brevard and State of Florida, have invented a new, original, and ornamental Design for an Ash Tray, of which the following is a specification, reference being had to the accompanying drawing forming part thereof wherein:

Figure 1 is a perspective view of an ash tray, showing our new design.

Figure 2 is a side elevational view.

The opposite end of the device to that shown is substantially plain.

We claim:

The ornamental design for an ash tray, as shown and described.

ORVIN H. CHANDLER.
WILLIAM W. CHANDLER.
